[57] CLAIM

The ornamental design for a can dispenser and holder, as shown and described.

DESCRIPTION

FIG. 1 is a top, front, and right side perspective view of a can dispenser and holder showing the first embodiment of my design;

FIG. 2 is a right side elevation view thereof;

FIG. 3 is a top elevation view thereof;

FIG. 4 is a bottom elevation view thereof;

FIG. 5 is a left side elevation view thereof;

FIG. 6 is a front elevation view thereof;

FIG. 7 is a rear elevation view thereof;

FIG. 8 is a right side elevational view of a second embodiment thereof, the only difference from the first residing in the appearance of the side elevations; and,

FIG. 9 is a right side elevational view of a third embodiment thereof, the only difference from the first residing in the appearance of the side elevations.
